UNITED STATES PATENT OFFICE.

WILLIAM A. C. JACKO, OF BRADDOCK, PENNSYLVANIA.

FLY SWATTER.

Application filed January 25, 1926. Serial No. 83,644.

This invention relates to fly swatters and has particular reference to the manner in which the striking head is connected with the handle.

One object of the invention is to provide a very strong and durable connection between the handle and striking head and prevent the head from being bent at its connection with the handle and broken loose after the fly swatter has been used a comparatively short length of time.

Another object of the invention is to so form the connection between the handle and striking head that the head may have swinging movement independent of the handle and thereby permit the head to have flat contact with a table or the like when moved into engagement therewith by a striking motion.

Another object of the invention is to provide the handle with a clamping head adapted to be firmly connected with the handle and have tight gripping engagement with the flexible connection of the striking head.

Another object of the invention is to so connect the clamping head with the handle that it will be prevented from having pivotal movement relative to the handle.

This invention is illustrated in the accompanying drawing, wherein:

Figure 1 is a view showing the improved fly swatter principally in top plan with portions broken away;

Fig. 2 is a longitudinal sectional view taken on the line 2—2 of Fig. 1, and

Fig. 3 is a transverse sectional view taken on the line 3—3 of Fig. 1.

The handle which is indicated in general by the numeral 1 is formed from a strand 40 of stiff wire bent intermediate its length to provide a U-shaped hand-hold 2, the arms of which are brought together and twisted to form a shank 3. The shank 3 may be of any desired length. After the shank has been formed, the end portions of the wire 45 are bent to form a crosshead 4 which extends transversely of the shank from opposite sides thereof. This crosshead 4 forms an elongated eye having a forward bar 50 crimped intermediate its length to provide a lug 6 extending forwardly from the eye in alignment with the shank. While it is stated that the handle is formed of heavy wire bent and twisted as set forth above, it 55 will be obvious that the formation could be modified. It is important, however, that the

handle be provided with a crosshead at its forward end with which the coupling head 7 may be firmly connected.

The coupling head is formed of sheet metal and although tin is preferably used so that the cost will be reduced as much as possible, it will be obvious that other metals may be employed. The sheet metal blank is passed through the eye or crosshead 4 and bent to form jaws 8 and 9, one of which is provided with side flanges 10 adapted to be pressed into overlapping engagement with the side portions of the other jaw. These jaws are adapted to grip the reduced rear end portions of the flexible strips 11 and 12 which together form a flexible mounting for the striking head 13. After the reduced rear end portions of the flexible strips have been placed between the jaws 8 and 9 and the flanges 10 bent into overlying engagement with the jaw 8, rivets or similar fasteners 14 are passed through the jaws and are tightly clinched so that the jaws will be firmly held in operative engagement with the connecting strips 11 and 12. Certain of these rivets pass through the rear end portions of the strips 11 and 12 and, therefore, these strips will be positively retained between the jaws. Referring to Fig. 1, it will be seen that although the blank from which the coupling head is formed is bent about the forward bar 5 of the crosshead tilting movement of the coupling head will be prevented by the abutment lug 6 which extends forward between the jaws and effectively holds the coupling head against turning.

The strips 11 and 12 which cooperate to form the flexible connection between the coupling head 7 and striking head 13 are preferably formed of leather but may be a heavy fabric, such as canvas or any other material, having sufficient flexibility to permit free swinging of the striking head relative to the coupling head without danger of its being broken by repeated bending. It should be further noted that the connecting strip 12 is thicker than the strip 11 and, therefore, although free movement is permitted between the striking head and coupling head, the flexible connection will tend to normally retain the striking head substantially in alignment with the shank 3 and hand-hold 2 of the handle. The forward end portions of the coupling strips are of greater width than their rear end

portions and, when engaged with opposite faces of the wire from which the striking head is formed, cover the rear end portion of the striking head for its full width. The 5 sides of the forward end portions of the connecting strips are enclosed by the binding 15 provided for the marginal portions of the screening from which the striking head is formed and the connecting strips may be 10 held in engagement with the sheet of screening by stitching 16 or in any other desired manner.

When the swatter is in use, it is operated in the ordinary manner. The striking head 15 may have flat contacting engagement with the table or other surface upon which a fly is resting as the leather from which the connecting strips are formed is flexible and, therefore, the striking head is permitted of 20 free swinging movement independent of the handle. There will be no danger, however, of the striking head being quickly broken from the handle as the bending takes place across the portion of the connecting strips 25 between the forward ends of the jaws of the coupling head and the rear end of the fabric from which the striking head is formed. Therefore, the fly swatter will be very durable.

Having thus described the invention, I 30 claim:

1. A fly swatter comprising a striking head, a handle including a shank and a coupling head at the forward end of the shank, 35 said coupling head including jaws and means for securing the jaws in a gripping position, and strips of pliant material secured in overlapping relation to opposed faces of the rear end portion of said striking head and extending rearwardly therefrom and gripped between the jaws of said coupling head, one strip being thicker than the other and serving to normally retain the striking head substantially in alignment 40 with said handle.

2. A fly swatter comprising a striking head, a handle including a shank and a

crosshead at its forward end, a lug extending from said cross head, a coupling head consisting of a strip passed about said 50 crosshead and projecting forwardly therefrom to form jaws adapted to be secured in a gripping position, said coupling head being held against turning upon the crosshead by said lug, and a connection of pliant material secured in overlapping relation to the rear end portion of said striking head and projecting rearwardly therefrom and secured between the jaws of said coupling head. 60

3. A fly swatter comprising a striking head, a handle including a shank and a crosshead at its forward end including a forward bar having a portion projected forwardly to form an abutment lug, a coupling 65 head consisting of a strip of metal passed through said crosshead and having its end portions projecting forwardly above and below said bar to form gripping jaws, said coupling head being held against turning 70 upon said bar by said lug, and a connection of pliant material secured to said striking head and extending rearwardly therefrom and secured between the jaws of said coupling head. 75

4. A fly swatter comprising a striking head, a handle including a shank and a crosshead at its forward end including a forward bar having a portion projected forwardly to form an abutment lug, a coupling 80 head consisting of a strip of metal passed through said crosshead and having its end portions projecting forwardly above and below said bar to form gripping jaws, said coupling head being held against turning 85 upon said bar by said lug, and strips of pliant material secured against opposed faces of the rear end portion of said striking head for approximately the full width thereof and having reduced portions extending rearwardly therefrom and secured between the jaws of said coupling head. 90

In testimony whereof I affix my signature.
WILLIAM A. C. JACKO. [L. S.]
